GRILLE BLADE AND CROSS-BAR ASSEMBLY

Lee B. Green, Lakewood, Ohio, assignor to The
Globe Machine & Stamping Company, Cleve-
land, Ohio, a corporation of Ohio

Application October 4, 1934, Serial No. 746,873

15 Claims. (Cl. 293—54)

My invention relates to metal grilles of the class in which U-sectioned and generally parallel blades are connected to each other by cross-members, which cross-members may be both 5 grille-end members connecting end portions of the blades, and intermediate cross-members connecting parts of the blades spaced from the end members.

Generally speaking, my invention aims to provide a simple and inexpensive construction of metal cross-members which will permit U-sectioned metal blades to be anchored securely to these cross-members by speedy and inexpensive operations without requiring the providing of any 10 slots, tabs or other anchoring provisions on the blades; and also aims to provide a cross-member construction for this purpose which will be equally advantageous for the end bars by which such a grille is usually supported, and for either plain 15 or bead-ornamented intermediate cross-bars.

In modern passenger automobiles, it has become quite customary to guard the frontal air-admitting aperture in the so-called radiator shell by a metal grille consisting of generally parallel 20 blades extending across the said aperture, these blades having their end portions connected by cross-members (commonly called end bars) which are fastened to, and concealed by, portions 25 of the front of the radiator shell. For such so-called "automobile radiator grilles," sheet metal blades of a rearwardly open U-section have proven particularly advantageous, both because of the finished appearance of their forwardly presented convex U-backs and because of the 30 strength and rigidity which a U-formation affords even when the blades are made of quite thin sheet steel.

However, the U-section which affords the just 35 recited advantages has the disadvantage of making it difficult to fasten such blades inexpensively to the end members of the grille, since the end portion of each blade usually had to be deformed to present a flattened part which then could be welded or brazed to an end member. Such welding operations add considerably to the manufacturing cost of the grille, and the difficulty of providing the needed blade-end deformations has 40 lately been increased by the desire for quite narrow blades, as for example, U-sectioned blades 45 with a clear spacing of less than three-thirty-seconds of an inch between the blade webs.

Moreover, the heretofore employed methods 50 of securing intermediate cross-members to U-sectioned blades have limited the positioning of such cross-members, so that the latter (when of simple

construction) could not extend in front of the blades to afford conspicuous cross-bar effects for enhancing the appearance of the grille.

Generally speaking, I overcome all of the above 5 recited limitations of the heretofore customary metal grille constructions by providing cross-members each of which presents two parallel webs, which webs have aligned slots through which the blades can readily be slid, and by thereafter anchoring each blade to each cross-member by 10 an expeditious deforming of the portions of the blade webs which are disposed between the said two parallel webs on each cross-member. Then, by otherwise varying the cross-members I adapt 15 them for use either as end members of the grille, as plain intermediate cross-members, or as bead-ornamented intermediate cross-members. Also, by other easily made variations, I adapt the end members for use with upright blades spanning 20 apertures which have bowed upper and lower ends.

Illustrative of my invention,

Fig. 1 is a fragmentary full-length perspective view of a flat-fronted grille of rectangular shape embodying all features of my invention.

Fig. 2 is an enlarged rear elevation of the upper 25 portion of the same grille.

Fig. 3 is an enlarged rear perspective view of a portion of the upper grille part shown in Fig. 2.

Fig. 4 is a horizontal section taken along the 30 line 4—4 of Fig. 3.

Fig. 5 is an enlarged perspective view of a portion of the upper end member of the grille.

Fig. 6 is an enlarged side elevation of the upper 35 portion of the grille.

Fig. 7 is an enlarged view of the part of a blade which extends through and beyond the two parallel webs of one of the cross-members, showing how the blade was deformed to anchor it.

Fig. 8 is an enlarged perspective view of the tip 40 portion of a punch suitable for effecting this blade-deforming.

Fig. 9 is an enlarged perspective view of a portion of an unornamented intermediate cross-member, such as the one next below the upper 45 end member in Fig. 1.

Fig. 10 is a fragmentary plan view of the metal blank from which the cross-member of Fig. 9 was formed, drawn on a smaller scale.

Fig. 11 is an enlarged side elevation of the mid-height portion of Fig. 1, showing a cross-member having an ornamenting molding sleeved on it.

Fig. 12 is a fragmentary perspective view of the cross-member of Fig. 11 alone.

Fig. 13 is a vertical section through a portion 55

of an upwardly bowed upper end member, taken in a plane parallel to the riser webs of that member and intersecting the perforations in the spaced webs.

5 Fig. 14 is a similarly taken vertical section through a part of a V-sectioned lower end member.

10 Fig. 15 is a vertical section taken along the rear edges of blades and through both perforated webs of an end member, and also through the punch used for bowing these webs apart, showing the resulting curving of the blades with a relatively wider spacing of the said perforated webs than that shown in Figs. 2, 3 and 6.

15 In Figs. 1 to 6, the upper end member (of which the lower end member is an inverted counterpart) consists of two angle irons each presenting one horizontal web and one vertical web, one of the angle irons being disposed within the angle of the other one. This inner angle iron has its horizontal web 1 freely spaced upwardly from the horizontal web 2 of the other angle iron by a distance which, for reasons hereafter recited, is desirably approximately one half larger than the clear spacings S between the parallel webs of the U-sectioned blades B of the grille.

20 The upright web 3 of the inner angle member is rigidly fastened to the inward face of the upright web 4 of the outer angle member, as for example by spot-welds, one of which is indicated at W in Fig. 3. Both of the upright webs may also have overlapping extension ears, such as the ear 5 of Fig. 1, for receiving bolts fastening the end member to the radiator shell front (or other apertured member) which is to have its aperture spanned by the blades of the grille.

25 The horizontal (and therefore parallel) webs 1 and 2 of the end member are provided with aligned perforations P of counterpart size and spacing, each of which perforations has its bore corresponding to the cross-sectional exterior contour of one of the blades, and presenting its semi-cylindrical end toward the riser webs of the end member. Moreover, for use with coparallel blades, these perforations in each of the said horizontal webs have their longer axes A parallel to each other and have their semi-cylindrical ends equally spaced from the adjacent upright web.

30 After each blade has been slid through aligned perforations in the two horizontal webs 1 and 2, each blade presents laterally opposite portions of its two U-webs between the said horizontal webs, and I then bow these blade web portions away from each other, as shown in Fig. 2.

35 For this purpose I desirably employ a slightly tapering punch of circular cross-section and of a maximum diameter somewhat smaller than the clear space d (Fig. 2) between the superposed webs 1 and 2 of the adjacent end bar, this punch having a rounded tip as in Fig. 8. When such a punch is inserted forcibly between the said laterally opposite portions of the two webs of a blade, the punch distends each of these web portions and bends that web portion about the adjacent longitudinal edge of the slot P. Consequently, the part of a blade which extends through the superposed webs 1 and 2 is deformed (as shown separately in Fig. 7) to present bowed-apart web portions b between the said slotted webs of the adjacent end member, and the upper and lower parts b^1 and b^2 of each such bowed blade-web portion affords shoulders bearing respectively upwards against the upper slotted web 1 and downward against the lower slotted web 2 of the end bar.

40 The maximum diameter of the part of the punch which is thus forcibly inserted between the two webs of a blade necessarily must be greater than the maximum spacing S (Fig. 2) between these webs and less than the spacing d between the perforated webs 1 and 2 of the end-member; and if these blade webs were not connected by the U-back of the blade, the inserting of the punch between them would draw additional portions of these blade webs into the space between the two webs of the cross-member. However, the U-back of the blade does not permit this, so that the initially flat blade web portions between the two webs of the end member are stretched to the greater length needed for bowing them apart. 15

45 When the thickness of the blade webs is proportioned to their spread approximately as here illustrated, I have found it desirable to make the clear spacing d between the perforated webs of the end member at least $2\frac{1}{2}$ times the clear spacing S between the blade webs and to have the maximum diameter of the blade-entering port of the punch not more than twice the latter spacing. By doing so, I cause each deformed web portion to recurve at each end, as shown in Figs. 25 and 15.

50 In other words, by having the spacing between the perforated webs of the end member considerably exceed the sum of the maximum diameter of the punch and the joint thickness of the two blade webs, I avoid producing sharp bends in these blade webs, which would unduly weaken and might even tear these webs. However, I have also found that with the same size of punch and the same blade webs, I can secure a rigid anchoring when the spacing between the perforated webs of the end member is as much as four times the said clear spacing S between the webs of a blade, as in Fig. 16.

55 To enhance the rigidity of the fastening of the blades to an end member, I may also dispose the web perforations so that those in the perforated web 1 of the inner angle member have their bowed ends tangential to the inward face of the riser web 3 of that member (as shown in Fig. 5) thereby causing the U-backs of the blades to bear against the said riser web 3 of the inner angle member as shown in Figs. 3 and 6.

60 For unornamented cross-members, such as the two shown respectively above the mid-height (ornamented) cross-member in Fig. 1, I desirably employ the single-piece construction of Fig. 9 in which the two horizontal webs 8 and 9 are connected to each other by a riser web 10 which is exposed in front of the blades (as shown in Fig. 1) 65 after the blades have been anchored to it in the same manner as above described.

65 Such a single-piece cross-member can readily be formed by bending a metal strip, of which a portion is shown in Fig. 10 along the dotted bend lines 15 after the two rows of perforations P have been punched in this strip; and the spacing of all of perforations P from the plane of the inner face of the U-back 10 can be varied, thereby varying the extent to which this cross-member will project forwardly beyond the blades.

70 For a more ornamental effect, the channel-back of such a cross-member may be made wider than the distance between the oppositely directed faces of the perforated webs 8 and 9, and this channel-back 10a can then have its side edge portions 10b recurved and merging into the forward portions of the channel webs 8 and 9, as shown in Figs. 11 and 12.

75 After the blades have been anchored to this

cross-member (or even after the entire grille has otherwise been assembled and painted) a rearwardly slotted tubular ornamenting member can be slid over the forward portion of this cross-member. Such an ornamenting bead or molding, shown at 12 in Figs. 1 and 11, may be of chrome-plated or stainless steel to contrast with a darker finish of the body portion of the cross-member.

When a cross-member is thus to be ornamented (and also effectively widened) by an attached molding the perforations P in each web 8 and 9 of this member have their forward ends spaced sufficiently rearward from the recurved portions 10b of the channel-back 10a as to permit the recurved parts of the slotted molding to be disposed between the said recurved portions 10b and the forward edges of the blades.

In practice, cross-members of the above described three types—namely, end members, simple channel members, and bead-ornamented channel members—can all be used for cross-connecting the blades of a single grille, if all of these types have similarly spaced perforated webs all provided with aligned perforations slidably fitting the blades. Moreover, the spacing between such cross-members can readily be varied as desired, as also the spacings between the perforations P, and the same gang punches can be used for forming the perforations in the webs of members of these different types.

Since the blades are firmly gripped by the side walls of the perforations in both of the superposed webs of each here disclosed cross-member, this gripping also prevents the said webs from flexing either toward or away from each other, so that my cross-members are adequately rigid even when formed of quite thin metal.

Moreover, the two superposed webs of each cross-member can present non-planular faces to correspond to curved or otherwise shaped edges of the adjacent aperture in the radiator-shell front or other member which is to have an aperture spanned by the grille. For example, Fig. 13 shows the superposed webs 21 and 22 of an upper end member as bowed upwardly to a counterpart curvature, so that the perforations in each web can be formed with the same gang punch. Fig. 14 shows part of a lower end member in which the superposed webs 23 and 24 are bent flatwise to a V-section.

So also, the cross-sectional shape of each web perforation P can readily be varied to correspond to the exterior cross-section of the selected blades, and obviously many other changes might be made without departing either from the spirit of my invention or from the appended claims.

I claim as my invention:

1. A metal grille comprising a plurality of parallel substantially upright blades of generally counterpart U-section, and a plurality of vertically spaced and rigid cross-members extending transversely of the said blades; each cross-member including two vertically spaced horizontal webs; both webs of each of the several cross-members being provided with aligned perforations each having a bore section corresponding to the peripheral contour of a blade, and each blade extending through aligned perforations in both webs of the cross-members; the portions of the two U-webs of each blade which are disposed between the two webs of each cross-member being bowed away from each other and presenting shoulders engaging the opposed faces of the said two webs.

2. An upright metal grille comprising a plurality of vertically spaced cross-members, each

of which members includes two vertically spaced horizontal webs and a rigid upright web-connecting portion interposed between the said webs, all of the said webs having counterpart and vertically aligned perforations; each of the said perforations having parallel side walls of equal length and having its end walls respectively flat and semi-cylindrical; and U-sectioned blades each extending through and exteriorly fitting vertically aligned perforations in both webs of each of the cross-members; all parts of each blade excepting the blade portions interposed between the two webs of each cross-member being of uniform U-section corresponding to the bore section of the said perforations; each of the said interposed blade portions having its U-web parts bowed away from each other, and each of the said bowed parts having its upper and lower portions respectively engaging the opposed faces of the two webs of the cross-member between which the said bowed parts are interposed.

3. A metal grille as per claim 1, in which each of the said bowed blade web portions has a portion thereof of an exterior curvature approximating, but not greater than, that of a cylinder of the diameter corresponding to the spacing between the spaced webs of the cross-member.

4. A grille as per claim 2, in which the web-connecting portion of each cross-member comprises two webs presenting upright faces and extending in the same direction respectively from the similarly disposed edges of the said two webs, the said upright-faced webs having overlapping portions thereof extending vertically beyond and one of the said webs, the said overlapping portions of the two webs being secured to each other.

5. In an upright metal grille, a blade-connecting member comprising two angle-bars of right-angled section, each angle-bar presenting one web upright and the other web horizontal, the horizontal webs of the two angle-bars being superposed in spaced relation to each other and provided with aligned slots of counterpart sizes, and the upright webs of the two angle bars being secured to each other; and U-sectioned blades each extending through aligned slots in the said two superposed horizontal webs, each blade corresponding in peripheral contour substantially to the cross-section of one of the said slots; the two U-web parts of each blade extending between the said horizontal webs of the blade-connecting member being bowed apart so that upper and lower portions of these blade web parts respectively engage the opposed faces of the two horizontal webs of the cross-member.

6. A metal grille comprising a plurality of spaced blades and substantially co-parallel blades of rearwardly open U-section, and cross-members spaced longitudinally of the blades; each cross-arm including in rigid formation two spaced webs having perforations aligning longitudinally of the blades, each perforation having a bore corresponding to the exterior cross-section of a blade, and each blade extending through aligned perforations in the cross-members; the portions of each U-web of each blade which extend between the two webs of a cross-member being bowed out of alignment with the parts of the web outside the said webs of the cross-member, and each such U-web portion having parts thereof bearing respectively against the opposed faces of the two webs of the cross-member between which it is disposed.

7. A metal grille as per claim 6, in which the clear spacing between the two webs of each cross-

member is approximately between 50 and 100 percent greater than the clear spacing between the U-webs of a blade.

8. A metal grille comprising a plurality of substantially co-parallel blades of rearwardly open U-section, and a cross-member comprising two angle-sectioned parts disposed one within the other and with their section angles opening in the same direction; the cross-member having contiguous webs of the said two parts secured to each other; the said contiguous webs presenting flat faces parallel to the common surface tangential of the U-backs of the blades, and the other webs of the said two parts being spaced from each other longitudinally of the blades and having their flat faces transverse of the axes of the blades; the said other webs having counterpart perforations, and each blade extending consecutively through two counterpart perforations in both of the said other webs of a cross-member; each blade exteriorly fitting the bore of each perforation through which it extends, and the part of each U-web which is disposed between the said two other webs being a segment of a tube having its axis transverse of the faces of the said contiguous webs, which tube segment has at least a portion thereof engaging the opposed faces of the said two other webs.

9. A metal grille as per claim 8, in which the U-backs of the portions of each blade which are disposed within the angle of one of the said parts of the cross-member bear against a flat face of the last named one part of the cross-member.

10. In a metal grille, a cross-member for connecting a plurality of substantially upright and co-parallel blades of counterpart rearwardly open U-section comprising two angle-bars of unequal height disposed one within the other, the said angle-bars having the angles between their webs opening in the same direction, and each having its two webs extending respectively vertically and horizontally, the vertical webs of the two angle-sectioned parts being secured flatwise to each other and the horizontal webs of the said two parts extending rearwardly from the said vertical webs and being spaced from each other by a distance greater than the clear spacing between the U-webs of one of the blades; the said two horizontal webs having aligned perforations each corresponding substantially in its bore

area to the exterior cross-sectional contour of a blade.

11. A cross-member for a parallel-bladed grille, as per claim 10, in which each perforation presents a rounded end toward the inward face of the vertical web of the inner angle-bar. 5

12. A cross-member for a parallel-bladed grille, as per claim 10, in which each perforation presents a rounded end flush with the rearward face of the vertical web of the inner angle 10 part.

13. A cross-member for connecting a plurality of co-parallel blades of counterpart rearwardly open section, comprising a channel-sectioned metal member having its channel webs provided with similarly spaced perforations each of a bore corresponding to the exterior cross-sectional contour of one of the blades, the channel-back of the said member being wider than the spacing 15 between the oppositely directed faces of the said 20 two channel webs and having its side edges recurved and merging respectively into the forward portions of the said channel webs.

14. A blade-connecting cross-member as per claim 13, including an ornamenting moulding of 25 rearwardly slotted tubular section straddling the said channel-back.

15. A cross-member for connecting a plurality of co-parallel blades of counterpart rearwardly open section, comprising a channel-sectioned 30 metal member having its channel webs provided with similarly spaced perforations each of a bore corresponding to the exterior cross-sectional contour of one of the blades, the channel-back of the said member being wider than the spacing 35 between the oppositely directed faces of the said two channel webs and having its side edges recurved and merging respectively into the forward portions of the said channel webs; and an ornamenting moulding of rearwardly slotted 40 tubular section straddling the said channel-back, the said perforations in the channel webs of the said channel-sectioned member being spaced sufficiently rearward from the said recurved portions of the channel-back of that 45 member so that the portions of the moulding adjacent to the slit in the latter can be disposed between the said recurved portions and a plane tangential to the forward ends of the perforations in the channel webs of the said member. 50
